ELECTRICAL CONNECTOR

Peter J. Bach, Brentwood, and James H. Simpson,
St. Louis, Mo., assignors to Mines Equipment
Company, St. Louis, Mo., a corporation of Mis-
souri

Application April 30, 1945, Serial No. 591,164

10 Claims. (Cl. 287—76)

1

This invention relates to improvements in couplings or connectors, particularly electrical connectors of the quick detachable, friction grip plug-and-socket type. The objects of the invention are to devise a strong, simple, economical and efficient electrically conductive connector of the above type that will provide increased friction between the plug and socket members at their surface of contact and thus prevent separation or loss of surface contact of said members under service conditions and that will provide for cleaning the contact surface of the socket member by the plug member during the engagement and disengagement thereof. The invention consists in a hollow cylindrical plug member with oblique circumferentially spaced slits therein and a member having a cylindrical socket of smaller diameter than the slit portion of said plug member, whereby endwise insertion of said plug member in said socket member will compress the slit portion and cause it to bear resiliently against the wall of said socket. The invention also consists in providing the slit hollow cylindrical plug member with a central reinforcing pin or core and in providing an annular space between said plug and core adapted to permit the slit portion to spring radially inwardly when said plug is forced into said socket. The invention also consists in the electrical connector and in the parts and combinations and arrangements of parts hereinafter described and claimed.

In the accompanying drawing, which forms part of this specification and wherein like symbols refer to like parts wherever they occur,

Fig. 1 is a side elevational view of an electrical connector embodying my invention,

Fig. 2 is an end elevational view thereof,

Fig. 3 is a cross-sectional view on the line 3—3 in Fig. 1,

Fig. 4 is a side elevational view of the plug member of the connector,

Fig. 5 is a central longitudinal sectional view of the socket member of the connector,

Fig. 6 is an enlarged central longitudinal section on the line 6—6 in Fig. 4,

Fig. 7 is a cross-sectional view on the line 7—7 in Fig. 6; and

Fig. 8 is an enlarged fragmentary central longitudinal sectional view on the line 8—8 in Fig. 1.

In the accompanying drawing, our invention is shown embodied in an electrical connector of the friction grip, axially engageable and disengageable plug-and-socket type. Said connector comprises an electrically conductive member 1 having a cylindrical axial socket 2 opening

2

through one end thereof and an electrically conductive member 3 having a reduced hollow cylindrical plug 4 at one end thereof adapted for endwise insertion in and removal from said cylindrical socket. Located within and extending from end to end of the tubular plug portion 4 of the member 3 is a central core or pin 5 that is press-fitted in or otherwise rigidly secured to said member at the inner end of said hollow plug portion. The pin 5 is of smaller diameter than the inside diameter of the hollow plug 4 so as to provide an annular clearance space 6 between said pin and plug.

In the engaged position of the plug and socket members 4 and 3, the annular shoulder 7 formed by the reduced tubular plug portion 4 of the member 3 abuts against the adjacent plug receiving end of the member 1. At their remote ends, each of the plug and socket members 4 and 3 has intersecting axial and diametral holes 8 therein adapted to receive the wires or cables (not shown) that are to be electrically connected by said members.

The tubular or hollow cylindrical plug portion 4 of the member 3 has end portions 9 of slightly smaller diameter than the cylindrical socket 2 in the member 1 and an intermediate portion 10 of larger diameter than said cylindrical socket. The tubular plug portion 4 of the member 3 has a plurality of longitudinal slits 11 cut therein that are disposed at oblique angles to the axis thereof and extend from end to end of the large diameter intermediate portion 10 of said plug portion and terminate in the smaller diameter end portions 9 thereof. These circumferentially spaced oblique or helical slits 11 divide the large diameter intermediate portion 10 of the hollow plug 4 into a series of relatively thick circumferentially spaced obliquely or helically disposed radially resilient sections 12. Thus, when the hollow cylindrical plug portion 4 of the plug member 3 is forced into the cylindrical socket 2 of the socket member 1, the circumferentially spaced obliquely or helically disposed sections 12 of the larger diameter intermediate portion 10 of said plug portion are forced radially inwardly and thus bear resiliently against the wall of said cylindrical socket with a pressure sufficient to frictionally resist endwise separation of said members. The annular clearance space 6 between the tubular plug portion 4 of the plug member 3 and the central pin or core 5 therein permits the slit large diameter intermediate portion 10 of said tubular plug portion to spring radially inwardly; and said pin also prevents

said tubular plug portion from being crushed or bent. The desired amount of friction between the plug and socket may be obtained by varying the diameter of the intermediate portion 10, the length and width of the helical or oblique sections 12 thereof and the width of the annular clearance space 6 between the reinforcing or supporting pin 5 and the hollow plug 4. The small diameter portion 9 at the entering end of the plug 4 serves as a pilot for guiding said plug into the socket 2; and the oblique or helical slits 11 provide cutting edges that function after the manner of a reamer to keep the wall of the cylindrical socket 2 bright and clean and electrically conductive.

What we claim is:

1. A connector comprising a member having a cylindrical socket therein and a member having a hollow cylindrical plug adapted for endwise insertion in said cylindrical socket, said hollow cylindrical plug having a straight cylindrical portion of larger diameter than said cylindrical socket, said straight cylindrical portion of said cylindrical plug having a plurality of helical slits therein, whereby said straight cylindrical portion is adapted when compressed in the smaller diameter cylindrical socket to bear resiliently throughout its entire length against the wall thereof and thus frictionally resist endwise separation of said members.

2. A connector comprising a member having a cylindrical socket therein and a member having a hollow cylindrical plug adapted for endwise insertion in said cylindrical socket, said hollow cylindrical plug having a straight cylindrical portion of larger diameter than said cylindrical socket, said straight cylindrical portion of said cylindrical plug having a plurality of circumferentially spaced slits therein extending obliquely to the longitudinal axis thereof, whereby said straight cylindrical portion is adapted when compressed in the smaller diameter cylindrical socket to bear resiliently throughout its entire length against the wall thereof and thus frictionally resist endwise separation of said members.

3. A connector comprising a member having a cylindrical socket therein and a member having a hollow cylindrical plug adapted for endwise insertion in said cylindrical socket, said hollow cylindrical plug having a straight cylindrical portion of larger diameter than said cylindrical socket, said straight cylindrical portion of said cylindrical plug having a plurality of circumferentially spaced longitudinal slits therein, whereby said straight cylindrical portion is adapted when compressed in the smaller diameter cylindrical socket to bear resiliently throughout its entire length against the wall thereof and thus frictionally resist endwise separation of said members, said second mentioned member having a cylindrical core rigid therewith that is disposed within and spaced from the hollow cylindrical plug thereof.

4. A connector comprising a member having a cylindrical socket therein and a member having a hollow cylindrical plug adapted for endwise insertion in said cylindrical socket, said hollow cylindrical plug having a straight cylindrical portion of larger diameter than said cylindrical socket, said straight cylindrical portion of said cylindrical plug having a plurality of circumferentially spaced slits therein extending at oblique angles to the longitudinal axis thereof, whereby said straight cylindrical portion is adapted when compressed in the smaller diameter

cylindrical socket to bear resiliently throughout its entire length against the wall thereof and thus frictionally resist endwise separation of said members, said second mentioned member having a cylindrical core rigid therewith that is disposed within and spaced from the hollow cylindrical plug thereof.

5. A connector comprising a member having a cylindrical socket therein and a member having an integral hollow cylindrical plug adapted for endwise insertion in said cylindrical socket, said hollow cylindrical plug having a straight cylindrical portion of larger diameter than said cylindrical socket, said straight cylindrical portion of said cylindrical plug having a plurality of circumferentially spaced slits therein extending at oblique angles to the longitudinal axis thereof, whereby said straight cylindrical portion is adapted when compressed in the smaller diameter cylindrical socket to bear resiliently throughout its entire length against the wall thereof and thus frictionally resist endwise separation of said members, and a cylindrical pin disposed in said hollow cylindrical plug axially thereof and spaced therefrom and press-fitted in said second mentioned member.

6. A connector comprising a member having a cylindrical socket therein and a member having a hollow cylindrical plug adapted for endwise insertion in said cylindrical socket, the socket entering end portion of said hollow cylindrical plug being of smaller outside diameter than said cylindrical socket and having a relatively thin wall and the portion of said hollow cylindrical plug adjacent to said entering end portion being of larger outside diameter than said cylindrical socket and having a relatively thick wall, said large diameter portion of said cylindrical plug having a plurality of circumferentially spaced slits therein extending at oblique angles to the longitudinal axis thereof, whereby said large diameter portion is adapted when compressed in the smaller diameter cylindrical socket to bear resiliently throughout its entire length against the wall thereof and thus frictionally resist endwise separation of said members.

7. A connector comprising a member having a cylindrical socket therein and a member having a hollow cylindrical plug adapted for endwise insertion in said cylindrical socket, the socket entering end portion of said hollow cylindrical plug being of smaller outside diameter than said cylindrical socket and having a relatively thin wall, and the portion of said hollow cylindrical plug adjacent to said entering end portion being of larger outside diameter than said cylindrical socket and having a relatively thick wall, said large diameter portion of said cylindrical plug having a plurality of circumferentially spaced slits therein extending at oblique angles to the longitudinal axis thereof, whereby said large diameter portion is adapted when compressed in the smaller diameter cylindrical socket to bear resiliently throughout its entire length against the wall thereof and thus frictionally resist endwise separation of said members, and a cylindrical pin press-fitted in said second mentioned member and disposed in said hollow cylindrical plug axially thereof and spaced therefrom.

8. A connector comprising a member having a cylindrical socket therein and a member having a hollow cylindrical plug adapted for endwise insertion in said cylindrical socket, said hollow cylindrical plug having thin wall end portions of smaller outside diameter than said cylindrical

socket and a thick wall intermediate portion of larger diameter than said cylindrical socket, said large diameter intermediate portion of said cylindrical plug having a plurality of circumferentially spaced longitudinal slits therein extending into said small diameter end portions thereof, whereby said large diameter portion is adapted when compressed in the smaller diameter cylindrical socket to bear resiliently throughout its entire length against the wall thereof and thus frictionally resist endwise separation of said members.

9. A connector comprising a member having a cylindrical socket therein and a member having a hollow cylindrical plug adapted for endwise insertion in said cylindrical socket, said hollow cylindrical plug having thin wall end portions of smaller outside diameter than said cylindrical socket and a thick wall intermediate portion of larger diameter than said cylindrical socket, said large diameter intermediate portion of said cylindrical plug having a plurality of circumferentially spaced longitudinal slits therein extending at oblique angles to the longitudinal axis thereof and into said small diameter end portions, whereby said large diameter portion is adapted when compressed in the smaller diameter cylindrical socket to bear resiliently throughout its entire length against the wall thereof and thus frictionally resist endwise separation of said members.

10. A connector comprising a member having a cylindrical socket therein and a member having a hollow cylindrical plug adapted for endwise insertion in said cylindrical socket, said hol-

low cylindrical plug having thin wall end portions of smaller outside diameter than said cylindrical socket and a thick wall intermediate portion of larger diameter than said cylindrical socket, said large diameter intermediate portion of said cylindrical plug having a plurality of circumferentially spaced longitudinal slits therein extending at oblique angles to the longitudinal axis thereof and into said small diameter end portions, whereby said large diameter portion is adapted when compressed in the smaller diameter cylindrical socket to bear resiliently throughout its entire length against the wall thereof and thus frictionally resist endwise separation of said members, and a pin rigid with said second mentioned member and disposed in said hollow cylindrical plug axially thereof, said pin being of smaller diameter than the inside diameter of said hollow plug to provide an annular clearance space between said pin and plug.
